UNITED STATES PATENT OFFICE

148,281

DESIGN FOR A LADY'S SANDAL

Arthur Capozzi, Bridgeport, Conn.

Application September 27, 1947, Serial No. 141,602

Term of patent 14 years

(Cl. D7—7)

To all whom it may concern:

Be it known that I, Arthur Capozzi, a citizen of the United States, residing at Bridgeport, county of Fairfield, and State of Connecticut, have invented a new, original, and ornamental Design for a Lady's Sandal, of which the following is a specification, reference being had to the accompanying drawings, forming part thereof.

Fig. 2 is a side perspective view thereof.

I claim:

The ornamental design for a lady's sandal, as shown.

ARTHUR CAPOZZI.
